UNITED STATES PATENT OFFICE.

ROBERT VINTON JONES, OF CLEVELAND, OHIO.

RAIL-JOINT.

SPECIFICATION forming part of Letters Patent No. 351,324, dated October 19, 1886.

Application filed June 24, 1886. Serial No. 206,169. (No model.)

To all whom it may concern:

Be it known that I, ROBERT VINTON JONES, of Cleveland, in the county of Cuyahoga and State of Ohio, have invented certain new and useful Improvements in Rail-Joints, of which the following is a specification.

This invention relates to railway-rail joints, and has for its object to provide a means of firmly uniting the abutting ends of railway-rails, being additional improvements for perfecting my Patent No. 322,828, dated July 21, 1885.

The invention consists in the combination of a flanged fish-plate with wedges and a chair, constructed and arranged as hereinafter described, and pointed out in the claims.

The flange of the flanged fish-plate has lugs which fit into notches made in the flange of the chair and the flange of the rails for the purpose of preventing the possibility of the rails opening at the joint.

In the accompanying drawings, Figure 1 is a perspective view of my device as seen attached to the rails. Fig. 2 is a cross section of same. Fig. 3 is a detached view of the chair and fish-plate combined in one piece. Fig. 4 is a detached view of the flanged fish-plate. Fig. 5 is a detached view of the locking-wedges. Fig. 6 is an outline view of the rails, showing the notches in the flange.

A B represent the abutting ends of two railway-rails.

C is a rail-joint chair, formed with an overlapping portion, C', for covering the flange of the rails A B. It also has an upward projecting portion, C'', which forms a fish-plate, designed to lie against one side of the web of the rails A B. The opposite side of the chair has an upward and overturned flange, C''. This chair and fish-plate I make in one piece.

D is a fish-plate, having a flange, D², which lies on the flange of the rails, and also has a narrow flange or lip, d, just above the bend or angle of the plate D and flange D'. The fish-plate is greatly stiffened by the lip or flange d, 45 and this with the wedges serves to bind the fish-plate firmly against the web of the rail, and thereby makes a firm joint without the use of bolts.

E F are wedges, which are forced in between 50 the flange C² and lip d, and bearing on the flange of the rails, thereby firmly locking all together. The top surface of wedge E is provided with inclined notches e e, and the wedge F has a hooked spring-arm, f, which engages 55 with the said notches for securing the wedges together. Lugs l l are made on the edge of the flange D', which extend into holes in the flange C² of the chair C, and also fit into notches n n in the edge of the flange of the rails. 60 Notches o are also made in the bend of the chair, into which the spikes lie which secure the chair to the tie.

Having described my invention, what I claim, and desire to secure by Letters Patent, 65 is—

1. The flanged fish-plate D, having lip or rib d, in combination with wedges E F and a chair, C, substantially as described, and for the purpose specified.

2. The combination, with two abutting rails, of the chair C, having parts C', C², and C'', the flanged fish-plate D, having lip d and lugs l l, and the wedges E F, for securing the rails together, substantially as and for the purpose 75 specified.

ROBERT VINTON JONES.
